UNITED STATES PATENT OFFICE.

CHARLES D. ROGERS, OF PROVIDENCE, RHODE ISLAND.

AUTOMATIC FIRE-EXTINGUISHER.

SPECIFICATION forming part of Letters Patent No. 364,299, dated June 7, 1887.

Application filed December 12, 1885. Serial No. 185,422. (No model.)

To all whom it may concern:

Be it known that I, CHARLES D. ROGERS, a citizen of the United States, residing at Providence, in the county of Providence and State of Rhode Island, have invented certain new and useful Improvements in Automatic Fire-Extinguishers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to apparatus for automatically extinguishing fires; and it consists, essentially, of a mounted fusible band, a weighted arm connected therewith, and a valve having its operating-lever supported by 20 a pivoted arm adapted to be tripped by the action of said weighted arm.

The invention further consists, in combination with said valve, levers, &c., of two push-buttons or electric connections, each adapted 25 to form a closed circuit by means of the action of the valve-lever whenever the latter is tripped or released, thereby sending out both local and general fire-alarms, all as will be more fully hereinafter set forth, and pointed out in 30 the claims.

The object of my invention is to provide a simple, inexpensive, yet efficient means for quickly extinguishing incipient fires in manu- 35 factories or dwellings, and at the same time to sound an alarm from a gong or bells electrically connected with the apparatus.

In carrying out the invention a strip of metal is supported around the room under tension overhead and firmly secured to a 40 weighted lever, (said strip, as before stated, being united at short distances by low-fusing solder.) Now, in case the metallic strip becomes unsoldered or disconnected the tension is thereby at once released, and the weighted lever in falling trips the arm supporting the free end of the valve-lever. The latter in turn drops to its limit, which movement opens the valve and allows the water to flow into the distributing or sprinkler pipes and extinguish 45 the fire.

For the purpose of illustrating my improved

fire-extinguishing apparatus I have prepared the accompanying two sheets of drawings, in which—

Figure 1, Sheet 1, represents a front elevation of the device complete as in use, a portion of the hub of the weighted lever being broken away to show the cam, which is adapted to engage the pivoted arm and release the weighted valve-lever whenever the metallic strip is unsoldered, the whole being shown as mounted on a frame or plate, which is secured to a wall, the "buttons," which form a part of the electric circuits, corresponding to the open position. Fig. 2 is a top view 65 of the same. Fig. 3 is a reduced side view, showing the metal strip disconnected, the valve-lever dropped to its limit, and the electric circuits closed, whereby the water is adapted to flow into the distributing-pipes, 70 and at the same time, by means of the electric connections, sending out both local and general fire-alarms. Fig. 4, Sheet 2, is a plan sectional view of a building or room provided with the improved fire-extinguishing apparatus, showing the general arrangement of the metallic strip and the distributing-pipes; and Fig. 5 represents a reduced sectional plan view, 75 showing the arrangement of local electric circuits connected with the apparatus to produce 80 local alarms, and also showing the device connected with an electric circuit, which in turn is connected with a fire-alarm station adapted to send out a general fire-alarm.

The following is a more detailed description 85 of my improvements, hereinafter claimed.

A, again referring to the drawings, designates a base or plate to which the several parts comprising the apparatus are attached. Secured to said plate is an inverted valve, V, of 90 ordinary construction, having an inlet-tube, m, and outlet n, the stem b² of the valve being connected with the weighted lever B, which is fulcrumed at b, whereby the lever in falling causes the said valve to open, and thus allow 95 the water to flow freely into the outlet-tube n, and thence to the distributing or sprinkling tubes n'. (See Fig. 4.)

At or near the free end of the lever B is pivoted at c, to the plate A, the two-arm or bell-crank lever D D', the arm D having a weight, W', adjustably secured thereto, the upper or

free end of the arm D' at the same time being secured to a strip of metal, H, which is supported by means of rolls H² and the corner segment-levers or guides h², as fully shown in Fig. 4. Said strip H is composed of a series of shorter pieces, which are united at h by means of solder fusible at comparatively low-heated temperatures. One end of the strip H is made fast to the building at h⁴, and the other end, as before stated, secured to the lever-arm D', all as clearly shown.

E indicates an arm pivoted at e³ to said plate A. The lower or free end, e², of the arm is provided with a hook or projection upon which the free end of the valve-lever B is adapted to rest, as shown in Fig. 1.

To the center or hub portion of the said two-arm lever D D' is formed a short arm or cam, C, which is adapted to engage the inner face of the said arm E.

P P' designate "push-buttons," which, by means of conducting-wires s s', are electrically connected with bells or gongs adapted to sound local and general fire-alarms, respectively, said alarms being automatically produced by means of dogs K K', adjustably secured to the lever B.

It is obvious that whenever the valve-lever is released the weight W thereof in falling 30 forcibly opens or unseats the valve V by means of the stem b² connected therewith. The back surface of the said dogs K K' at the same time coming in contact with the buttons P P', causes the latter each to close its respective circuit 35 and produce the alarms, as before stated.

The apparatus having been first arranged and connected substantially as shown in Figs. 1 and 4, the operation of the device upon the breaking out of a fire in any part of the room 40 provided with said extinguisher, as in a building, A², would be practically as follows: The metallic soldered strip H, however, is understood to be mounted overhead in suitable supports, the strip being under considerable tension and firmly secured at or near one end thereof to the end e of the lever-arm D'. Now, as just stated, upon the breaking out of a fire and the consequent rise of temperature in the room, one or more of the joints h become unsoldered, 45 thereby permitting the weighted arm D to move in the arrow-direction and causing the cam C to engage with and force the free end of the arm E from its engagement with the weighted valve-lever B, the latter thereby instantaneously falling to its limit, and at the same time 50 opening the valve V and allowing the water from a tank or other suitable source to flow from the inlet-pipe m into the pipe n and thence to the distributing-pipes n', from whence, by 55 means of the perforations n⁴, the water escapes to the floor below and extinguishes the fire. During this time also the dogs K K' engage the buttons P P', respectively, thereby closing the electric circuits and producing a local 60 alarm at the bell G, and a general alarm is sent out from the station or bell G², Fig. 5, R being a battery located in the local circuit, and

R' serving a similar office for the general circuit.

It is evident that the relative arrangement 70 of the buttons P P' may be changed without departing from the spirit of the invention—as, for example, the button P', by means of the action of the lever B and its dogs, may be pressed and the pressure removed before the 75 dog K engages its button P, or vice versa. The lever also may be provided with a stop, by means of which the said dog K will rest upon the button P and thereby produce a prolonged or continuous local alarm.

8c

It is obvious, also, that the connections may be arranged so as to produce open electric circuits by means of the dogs and falling lever B.

It is further evident that many changes in 85 minor details of construction and also in the relative arrangement of the several parts of the apparatus may be resorted to without departing from the spirit of the invention. Therefore I do not limit myself to the exact 90 construction shown and described.

I am aware that automatic fire-extinguishers adapted to operate by means of the fusing of solder at low temperatures have been made and used long prior to my present invention, and hence I do not broadly claim 95 such device; but

What I do claim, and desire to secure by United States Letters Patent, is—

1. The combination of a fusible band, a 100 pivotally-mounted weighted lever secured to said band, a cam or dog connected to and moving with the weighted lever, a suitably-mounted valve having a weighted arm connected therewith, and the pivoted rod E, 105 engaging the free end of the weighted arm, the whole constructed, arranged, and operating substantially as shown and hereinbefore set forth.

2. The combination, with a pivotally-mounted two-arm weighted lever, D D', having the fusible metallic band H secured thereto, and the cam C, forming a part of the lever's hub, of the valve V, having the weighted arm B connected therewith, and the loosely-mounted 115 rod E, supporting the outer or free end of the arm B, all constructed and arranged whereby the severing of the band H releases the lever D D', which in falling rotates the cam C, thereby violently forcing the rod E 120 from its engagement with the valve-arm B, substantially as shown and described.

3. The automatic fire-extinguishing apparatus hereinbefore described, consisting of the fusible band H, double-arm lever D D', attached to said band, the link E, cam C, valve V, and weighted valve-lever B, having dogs K K' adjustably mounted thereon, in combination with buttons P P', electrically connected with local and general fire-alarms, respectively, the whole constructed, arranged, and operating substantially as shown and set forth.

4. The combination, with the fusible me-

tallie band H, the weighted lever D D', having a cam, C, the pivoted supporting-rod E, and valve V, of the pivoted and weighted valve-lever B, having a dog, K, adjustably mounted thereon, and an electrically-connected circuit provided with a push-button, P, whereby the valve-lever in falling causes the rear surface of the dog to engage said button and automatically close the circuit, sub-

stantially as shown, and for the purpose set forth.

In testimony whereof I have affixed my signature in presence of two witnesses.

CHARLES D. ROGERS.
